UNITED STATES PATENT OFFICE.

CYRUS S. WERT, OF KENDALLVILLE, INDIANA.

CEMENT-BLOCK MACHINE.

No. 896,259.

Specification of Letters Patent.

Patented Aug. 18, 1908.

Application filed February 25, 1905. Serial No. 247,360.

To all whom it may concern:

Be it known that I, CYRUS S. WERT, a citizen of the United States, residing at Kendallville, in the county of Noble and State of Indiana, have invented a new and useful Cement-Block Machine, of which the following is a specification.

This invention relates to a cement block machine and consists in the novel construction and arrangement of parts hereinafter described, illustrated in the accompanying drawings, and particularly pointed out in the appended claims.

In the accompanying drawings:—Figure 1 is a perspective view of a cement block molding machine constructed in accordance with the invention. Fig. 2 is a vertical section of the same showing the cores in position. Fig. 3 is a sectional plan view of the machine with the cores in place. Fig. 4 is a vertical section of the machine on the line 4—4 of Fig. 2. Fig. 5 is a similar view of the machine as arranged on the formation of smaller or specially shaped blocks. Fig. 6 is an elevation 25 of one of the dividing plates employed in making a smaller block. Fig. 7 is a detail sectional view of one of the end plates of the mold showing the employment of an auxiliary filler to be used when the blocks are to be provided with recesses, as for instance, in the formation of joist receiving blocks. Fig. 8 is a detail perspective view of a finished block. Fig. 9 is a similar view of a portion of a joist receiving block.

Similar numerals of reference are employed to indicate corresponding parts throughout the several figures of the drawings.

The working parts of the apparatus are supported on a suitable frame 10 that preferably is formed of cast metal, and at one end of the frame is a fixed bed or table 11 that is provided with a pair of longitudinally disposed parallel ribs 12.

To the rear edge of the bed plate 11 is secured a back plate 13 of the mold, this being preferably secured in position as by bolts 14, so that when necessary it may be readily removed and a back plate of different size or contour substituted therefor. This back plate is provided with a plurality of openings 15, three of which are shown in the present instance, these openings being designed for the passage of core members 16, all of which are secured to a common cross bar 17 that may be moved to and fro in order to intro-

duce the cores within the mold box or remove them therefrom.

To the front of the bed plate are secured pivot lugs or ears 18 which may be cast integral with the bed plate if desired, and to these are pivoted lugs 19 extending from the lower edge of the front plate 20. This front plate may be swung down from the vertical position shown in Fig. 1 to the approximately horizontal position shown in Fig. 2, and in the latter position rests on a bracket 21 that projects from the frame or table of the machine.

To the opposite ends of the front plate are pivoted the end plates 23 of the mold box, and these may be swung from the vertical position shown in Fig. 3 to the approximately horizontal position shown in Fig. 1, and in the latter position the end plates rest on brackets 25 that project from the front plate 20. The opposite edges of the end plates 23 are provided with recesses forming flanges 25' of reduced width, and when in position one of the flanges fits against the end of the front plate, as will be seen on reference to Fig. 3, while the opposite flange fits against the end of the back plate, and is received by a bracket 26 carried by said back plate, the inner face of the bracket being inclined in order to exert a camming action on the flange and force the end plate inward to proper position on the mold box. Each end plate is provided with a plurality of projections or core members 28 and 29, that extend on the inner face of the plate within the recessed edges thereof, and are employed for the purpose of forming bonding recesses and air spaces in the ends of the blocks.

The front plate 20 forms a support for a removable carrier plate 30 that is provided with openings 31 for the passage of the core members 16 and is further provided with ribs or core members 32 for the formation of bonding recesses or grooves in the top or bottom of the finished block. This plate 30 has been termed the carrier plate for the reason that when the parts are turned to the position shown in Fig. 1, the plate forms a support for the block and is removed from the mold box together with said block, and supports the latter until the cement has set, a separate plate 30 being placed in the machine at each operation. To avoid the necessity of auxiliary fastening devices for the

plate 30, the end plates are provided with recesses before mentioned, and it will be noted, especially on reference to Fig. 3, that when the parts are in position to form a 5 mold box, the ends of the plate 30 are received within the recesses, and the core members carried by the end plates project from the ends of said plate 30 and firmly hold the same in place. When the mold is swung 10 over so that the carrier plate assumes a horizontal position, the opening of the end plates will immediately release the carrier plate, and the latter is free and may be readily removed together with the block 15 from the machine, and in this connection it is to be observed that the carrier plate and the front plate 20 of the mold are so constructed that said carrier plate may be freely moved outward from the bottom plate 20 33 of the mold.

The bottom plate 33 may be in the form of a cast metal plate, or may be formed of other material, or coated or plated with a non-corrodible material in order to avoid oxidation, and consequent injury to the blocks. 25 The plate as shown in the present instance is provided with a pair of marginal ribs 34 one of which, when in position, rests between the rear wall of the mold and one of the ribs 12. 30 The opposite rib is provided with openings for the reception of pins 34' that are carried by the lower portion of the front plate 20, the construction being such as to permit the ready removal of the bottom plate and the 35 substitution of another plate of different design therefor.

The bottom plate preferably has an ornamental face for the formation of imitation rock face, panel or other blocks, and by 40 placing the same in the bottom of the mold it is found that far better results may be attained than where the ornamental plate forms one of the side walls of the mold. The reason for this may be readily understood. 45 The plastic material shoveled or poured into the mold may be tamped down directly into all of the interstices of the ornamental face, and aside from this, the weight of all of the material which goes to form a block will 50 tend to firmly press the face to be ornamented against the bottom plate. A commercial block, however, could not be manufactured if the ornamental bottom plate was removed along with the block and the latter 55 allowed to set, for the reason that unequal contraction or expansion of the plastic material would tend to destroy the ornamental face, and if the cement set, it would be practically impossible to remove the ornamental 60 bottom plate, and again the expense of furnishing a separate ornamental bottom plate for each block manufactured would render it impossible to produce the blocks at a reasonable cost.

In order to hold the parts of the mold assembled, each of the end plates is provided with a bracket 37, to which is pivoted a handled locking lever 38, the latter being entered in a recess 39, there being one of said recesses at each end of the back plate 13 of the mold. To move the mold to closed position, that is, from the position shown in Fig. 1 to the position shown in the remaining figures of the drawing, it is merely necessary to grasp both handles 38 and first move the 70 end plates up to vertical position and then swing the whole of the front portion of the mold on the pivot lugs 18 until the flanges 25 of the end walls are entered in brackets 26, after which the locking levers 38 may be 75 turned and entered in the recess 39, firmly locking the parts in position; and to open the mold, the operation is reversed, it being found in practice that the swinging of the mold to turn the block at a right angle to the 80 molding position and the opening of the plates may be made by a practically continuous movement.

In order to avoid strain on the pins 34' which support the bottom plate 33, the 85 lower edges of the end plates are provided with lugs 40 that are moved under the ends of the bottom plate when the end plates are closed, and these lugs serve as supports for said bottom plate during the swinging movement of the mold and block from the position shown in Fig. 2 to the position shown in Fig. 1, and on the reverse movement to effect the closing of the mold box.

At a point near the rear end of the frame is 90 a cross bar 42 having an opening for the reception of a bar 43 that is connected at one end to the cross bar 17 of the cores, and the under side of bar 43 is provided with rack teeth 45 which are engaged by a toothed segment 46 carried by a transversely disposed shaft 47 adapted to suitable bearings on the frame of the machine. To one end of the shaft is secured an operating lever 48 which may be turned in order to move the core 95 members to the full line position shown in Fig. 2, or to the dotted line position shown in said figure.

In the present machine the cores are designed to be forced through a portion of the 100 plastic material which is placed in the mold before the cores are moved thereinto, and there is always more or less tendency of the cores to move from a direct line. To avoid this, the movement imparted through the 105 segmental rack is practically direct, and an auxiliary guiding means is employed in the form of a pair of parallel guide bars 49 that extend through suitable openings also formed in the cross bar 42, so that the cores cannot 110 be deflected from a straight course across the mold.

It will be observed on reference to Fig. 3

that all of the core members are separately and detachably secured to the cross bar 17, and this is of importance in that it permits the removal of one or more of the cores 16 5 when it is desired to form sectional blocks, or blocks of any peculiar contour, such, for instance, as those used for gables, corner pieces for bay-windows, and like purposes. To assist in the formation of these sectional blocks, 10 the back plate 13 and front plate 20 are provided with notches 52 for the reception of projecting ears 53 of division plates 54, and these plates may be arranged midway of the length of the mold, as shown in full lines in 15 Fig. 5, or at any other intermediate point either transversely of the mold, or in a direction oblique to the longitudinal plane of the mold, as shown by dotted lines in Fig. 5. When these sectional blocks are to be formed, 20 the ordinary bottom plate 33 is removed, and an auxiliary plate 33⁷ is employed, the auxiliary plate being provided with notches or grooves 56 for the reception of the lower edge of the division plate. When these blocks 25 are formed, it is impossible in some cases to use all of the cores, and the detachability of the cores is of especial value in this respect. In the position shown in Fig. 5, two of the cores have been removed and the openings of 30 the rear walls filled up by blocks or plates 58, while a single core member is shown in readiness to operate at the right of the mold box. In some cases it may be desired to form a block with recesses for the reception of joist 35 or other floor supporting devices, and for this purpose auxiliary filler strips 70 are secured to the end plates, as shown in Fig. 7. This forms a recess at the end of each block, and when two blocks are in alinement in the same 40 course, a recess of sufficient width will be formed to receive the end of a joist or the like.

In the operation of the machine, the parts are placed in the position shown in Fig. 2, 45 with the exception that the cores 16 are withdrawn to the position shown by dotted lines in said figure. The plastic material is then placed in the mold box up to a level about mid-way of the horizontal plane of the cores, 50 and is partly tamped in order to force the material down into the interstices of the ornamental bottom plate. The handled crank 48 is then operated and the cores are forced in to 55 the position shown in Fig. 2, forcing their way through the plastic material, and the ends of the cores entering the openings 31 formed in the carrier plate 30 for the purpose, so that both ends of the cores will be firmly 60 held in place. The mold box is then filled up with plastic material, and, after tamping, the excess material is struck off and the block is ready to be removed. The cores are now withdrawn by reversing the movement of the crank 48, and the locking levers 38 are then

turned to disengage the same from the recesses 39 after which, the end plates being still held in vertical position, the front plate, the carrier plate, the bottom plate, and the end plates are all swung on the pivot lugs 18 until the block assumes a position at a right 70 angle to the molding position. The end plates are then turned down to the position shown in Fig. 1 and the carrier plate may then be slid forward in order to remove the ornamental face from the mold plate 33, 75 after which the carrier plate, together with the block, is removed from the machine, and another carrier plate inserted in readiness for a second operation.

In the formation of blocks of this class, it 80 is usual to employ two air chambers spaced by a central web or partition extending transversely of the block and of considerable weight, and in the removal of the block from the machine and in subsequent handling, it is 85 found that the excessive weight caused by this web at the center of the block often results in cracking or other injury. To avoid this, the machine forming the subject of the present invention is designed to manufacture 90 blocks having somewhat smaller air chambers spaced by webs that are so arranged as to more evenly distribute the weight, and thus avoid danger of injury to the block during handling. It will be further observed 95 that the blocks are provided with bonding grooves on both ends, and on either the top or bottom, so that after the mortar has set, it will be practically impossible to dislodge 100 them, and at the same time the upper and lower faces of the block are of extensive area in order that the mortar bond may be sufficient to firmly hold the blocks in place.

Having thus described the invention, what is claimed is:—

1. In a machine for molding blocks of plastic material, the combination with a back plate, of a pivotally-mounted front plate having a plurality of projecting pins, a detachable bottom plate having openings for the reception of said pins, end plates pivoted to the front plate, and lugs projecting from said end plates and serving by engagement with the bottom plate to support the same during its movement to and from molding 115 position.

2. In a machine for molding blocks of plastic material, the combination with a back plate having cam-faced brackets, of a pivoted front plate, a bottom plate carried thereby, and end plates pivoted to the front plate, said end plates having reduced flanges adapted to be engaged by the cam faces of said brackets.

3. In a machine for molding blocks of plastic material, the combination with a rigid back plate having cam-faced brackets, of a pivoted front plate, a bottom plate support-

ed thereby, end plates pivoted to the front plate and having reduced flanges at its opposite edges, the flanges of the free ends of said end plates being engaged by the cam faces of the brackets and forced to closed position, and locking levers carried by said end plates and serving to engage the rigid back plate.

In testimony that I claim the foregoing as my own, I have hereto affixed my signature in the presence of two witnesses.
